COOLING OF GASEOUS MIXTURES

Paul Maurice Schuftan, Richmond Hill, England,
assignor to The British Oxygen Company Limited, London, England

Application March 28, 1940, Serial No. 326,466
In Great Britain March 24, 1939

9 Claims. (Cl. 62—122)

This invention relates to the cooling of gaseous mixtures, and is particularly applicable to a process and apparatus for precooling and prepurifying gaseous mixtures in periodically alternating regenerators or cold storers.

During the cooling of the gaseous mixture in one of such regenerators, condensation will occur on the surface of the storage mass. In the case of coke-oven gas, for example, water vapour, carbon dioxide, hydrogen sulphide and also propylene, propane and other relatively high boiling point hydrocarbons will be condensed and retained in the regenerator. It is essential that such condensates retained in the regenerator be completely re-vaporised and sublimated during the period when the regenerator is being cooled.

Periodically alternating regenerators employed for cooling gaseous mixtures were usually provided with a lagging of heat insulating material, but no material was found in practice to be absolutely non-conductive of heat. Consequently, a small amount of heat hitherto unavoidably leaked into the regenerators.

It was therefore necessary during the cooling down period to compensate for such influx of heat by introducing the cooling gas at a correspondingly lower temperature than that which would have been required in the next reversal period for cooling the warm gas to the desired temperature, if no influx of heat had occurred. This practice necessarily resulted in an increase of the temperature difference at the cold end of the regenerators, and this extra temperature difference made the revaporation or resublimation of condensates deposited in the regenerators more difficult.

It was also necessary to maintain high pressure ratios for the purpose of insuring the complete removal of the condensates during the cooling down period and of avoiding an accumulation of said condensates with consequent danger of obstruction in subsequent steps. Thus, higher pressure ratios between the warm and the cold gas were employed than would have been necessary if no heat could have entered the regenerators, that is to say, if the regenerators could be operated as an ideal adiabatic system. It will be appreciated that the higher pressure ratios employed resulted in high power consumption for the separation process.

According to the present invention, in a process for precooling and prepurifying gaseous mixtures by means of periodically alternating regenerators surrounded by heat insulating material, interference with the thermal conditions in the regen-

erators by the influx of heat from an exterior source is prevented. This is accomplished by absorbing heat from the insulating material in an amount sufficient to compensate for the amount of heat passing through the insulating material from the exterior to the regenerators.

By providing a cold shield in accordance with the invention it is possible to obtain a lower temperature difference at the cold end of the regenerators and to operate with a lower pressure ratio between the gas in the warming up and cooling down periods with a consequent increase in the efficiency of the plant.

Alternatively, if the pressure ratio be maintained higher than the minimum necessary for revaporation, the provision of the cold shield will result in a substantial decrease in the content of impurities in the pre-cooled gases. This is of particular advantage in cases such as the treatment of coke-oven gas for extracting ethylene, where the condensation range of the impurity—carbon dioxide—partly overlaps that of ethylene.

In both cases owing to the reduced temperature difference at the respective cold ends of the regenerators, the gas can now be precooled to a lower temperature than would be possible if no cold shield were provided. In the former case, the amount of impurities left in the precooled gas will not be decreased but there is the advantage of operating with a reduced working pressure with a considerable saving in power; in the latter case the amount of impurities is reduced in proportion to the increased working pressure.

The cold required for establishing the cold shield may be derived from any convenient source of cold. A part of the fluids from a later cooling stage may be diverted and circulated around the peripheral portions of the storage material. For example, where a refrigerating cycle is used to obtain additional cold at a later stage, a part of the refrigerating medium in the cycle may be diverted for this purpose in liquid or gaseous form. By using a liquid a larger amount of cold is available at the cold end of the regenerators and as a result of the vaporisation of the liquid the available cold progressively decreases towards the warm end of the regenerators. As the cold losses through the lagging also progressively decrease towards the warm end, the use of a liquid in the cold shield permits of a ready adjustment of the supply of cold to the demand.

An independent supply of cold equivalent to the ingress of heat from the exterior into the regenerators offers a further advantage affecting

the conditions of heat exchange and cold production in the plant where the regenerative cooling is combined with cooling by means of tubular heat exchangers. If, for instance, the cold is partly or wholly produced by compressed gas of which a part passes through a liquefier cooled by cold expanded gas, while the balance is adiabatically expanded in an engine, and if a part of the liquid obtained is used in the cold shield, the amount of cold gas returning into the liquefier is diminished, and therefore a greater proportion of the compressed gas than before can be expanded in the engine. This results in an increased cold production. Alternatively, if the amount of gas expanded in the engine is kept the same as before, the temperature difference in the liquefier increases and its surface can therefore be diminished.

One embodiment of the invention is shown by way of example in the accompanying drawing in which:

Fig. 1 shows in elevation and somewhat diagrammatically a pair of regenerators encased in the usual lagging;

Fig. 2 is a plan view of Fig. 1, the lagging overlying the regenerators being removed in order to expose the cold shield;

Figs. 3 and 4 are sectional drawings of parts of the apparatus on an enlarged scale, showing the preferred shape and method of mounting of the cold shield; and

Fig. 5 depicts a diagrammatic representation of a process according to the invention.

Referring to the drawing, two regenerators 5 and 6, each containing a storage mass and arranged for alternate operation, are mounted in a lagging consisting of heat insulating material 7 enclosed in an outer casing 8. The gases traverse the two regenerators in opposed directions as indicated by the arrows A and B, the coldest parts of the regenerators being at the upper ends.

In order to compensate for the ingress of heat to the storage mass, the regenerators are, in accordance with the invention, provided with a cold shield, which in the example illustrated is shown to be a helical tube 9 through which a liquefied gas is circulated, the inlet being at the upper end of regenerator 5 and the outlet at the lower end of regenerator 6, the direction of cold fluid through the tube being indicated by the arrows C and D. The liquid will be vaporised after traversing some of the turns, say five turns, of the helical tube 9.

As shown, the pitch of the helical tube increases progressively towards the lower end: the pitch is determined by the temperature gradient in the regenerators and the heat transfer conditions.

While it is generally convenient to use metal both for the cold shield and for the walls of the regenerator, it may, in view of the high heat conductivity of the metal, and the high heat transfer coefficient of boiling liquid, be necessary to reduce the rate of heat conduction between the wall of the regenerator and those turns of the helical tube in which the liquid vaporises, in order to avoid the regenerator walls being under-cooled locally. As a matter of fact, such an under-cooling of the regenerator wall and subsequently of the gas traversing the regenerator could cause solidification of one or more constituents of the gas with attendant risk of local obstructions in the storage mass.

As shown on an enlarged scale in Fig. 3, the reduction in heat conductivity may be achieved

5 by inserting between the regenerator wall 10 and the helical tube 9 a layer of heat insulating material 11. A plurality of brackets 12, spaced at intervals and secured to the wall 10 may be provided to hold the tube 9 in position.

At the lower or warmer parts of the regenerators, where the liquid has become vaporised, the tube 9 may be secured directly to the wall 10, as, for example, by solder 13 (Fig. 4).

10 The helical tube may, in cross section, be circular, rectangular, or other convenient shape, but it is preferred that the side adjacent to the regenerator wall be substantially flat, as is shown in the drawing, in order to provide good heat transfer conditions between the tube and the regenerator.

15 In order to minimise cold losses by convection, it is usually the practice to mount in a common casing the regenerators and other units, such as tubular heat interchangers and rectification columns in which further cooling and separation of the gases which are pre-cooled in the regenerators takes place, the whole being packed in heat insulating material.

In such cases, cold losses in the regenerators occur only on the side remote from the other units and, as shown in Fig. 2, the cold shield need then extend only over those parts of the regenerator walls from which cold losses occur.

An arrangement of apparatus wherein a part of a gas to be separated is compressed to a slight pressure and cooled in regenerators, while another part is compressed to a high pressure and cooled by expansion, is illustrated diagrammatically at Fig. 5. The apparatus shown comprises two regenerators 5, 6 arranged for alternate operation as a regenerative system in a manner well known to the art.

40 When separating air, for example, the major portion of the air is compressed to a slight pressure and passes through regenerator 5, as shown by the arrows in the figure relative to a single reversal period, it being assumed that regenerator 5 has been precooled in the previous period as described infra. The air then passes into a separating device 1, which may be of any appropriate form, such as a rectification column with the usual condenser and vaporiser, as those skilled in the art will understand. The minor portion of the air is compressed to a high pressure, is cooled in a tubular heat interchanger 2, is expanded through the throttle valve 3, and thence passes into the separator 1. In the separator the air is separated into an oxygen fraction and a nitrogen fraction in a manner well known to the art. The nitrogen fraction is returned into regenerator 6 to cool the same for the succeeding reversal period. The oxygen fraction passes through the tubular interchanger 2 in heat exchange with the high pressure air.

45 Before entering the heat interchanger 2, a small portion of the cold oxygen fraction from the separator 1 is branched off and supplied to a cold shield 8 which, as shown in detail in Figs. 1 and 2, extends wholly or partially around the regenerators.

If the expansion of the high pressure air through the throttle valve 3 results in the production of an insufficiently low temperature in said air, a further amount of heat can be absorbed therefrom by passing a portion of the high pressure air through an expansion engine 4, with recovery of external work. The portion of the air which is thus expanded is then re-

united with the air expanded through the throttle valve 3.

It will be appreciated that, in certain cases, especially where the cold for the cold shield is derived from a cold gas, the amount of cold gas passed through the cold shield may diminish progressively or in stages towards the warm end of the regenerators. Further, instead of using a helical tube for the cold shield, the storage mass of the regenerator may be housed within the inner vessel of a double walled container, the space between the two walls being adapted for circulating a cold fluid and thereby constituting the cold shield.

For the cold shield, any convenient cooling medium may be used, but in the case of a liquid its boiling point should be at a temperature somewhat lower than the lowest temperature to which the gas traversing the regenerators has to be cooled. In the case of the separation of air, either liquid nitrogen or liquid oxygen may be used, while in the case of the extraction of ethylene from coke oven gas, for instance, liquid methane would be a suitable cooling fluid.

I claim:

1. In a process for precooling and prepurifying a gaseous mixture which includes passing said mixture through one of a set of periodically alternating regenerators surrounded by heat insulating material, and passing gases emerging therefrom into tubular heat exchangers having a heat absorbing fluid, the improvement comprising diverting a part of the heat absorbing fluid from at least one tubular heat exchanger, and absorbing sufficient heat from the heat insulating material in said heat absorbing fluid to compensate for heat passing through said material from external sources to the regenerators.

2. In a process for separating a gaseous mixture into at least two components which includes compressing a portion of said gaseous mixture to a slight pressure, passing said compressed portion through a precooled regenerator surrounded by heat insulating material to cool said portion, compressing the remainder of said gaseous mixture to a high pressure, dividing said remainder into two highly compressed portions, passing one of said highly compressed portions into a tubular heat exchanger having a heat absorbing medium, expanding said highly compressed portion through an expansion valve, adiabatically expanding the other highly compressed portion, passing both the expanded highly compressed gas and gas emerging from the regenerator into a separation device, and recovering at least one component thereof, the improvement comprising passing at least a part of the component recovered into the heat insulating material surrounding the regenerator, and absorbing therein sufficient heat to compensate the amount of heat passing through said heat insulating material from external sources to the regenerator.

3. An improved heat transfer device for precooling and prepurifying a gaseous mixture which comprises a pair of alternating regenerators surrounded by heat insulating material, and a conduit in said heat insulating material forming a cold shield over said regenerator walls from

which cold losses occur for conveying a heat absorbing fluid therethrough whereby heat from external sources passing through said heat insulating material can be absorbed.

5 4. An improved heat transfer device for precooling and prepurifying a gaseous mixture which comprises a regenerator surrounded by heat insulating material, and a helical conduit extending around the regenerator for conveying a heat absorbing fluid whereby heat passing through the heat insulating material from external sources to the regenerator can be absorbed.

15 5. The heat transfer device set forth in claim 4 wherein the pitch of said helical conduit increases from the cold end of the regenerator toward the warm end of the regenerator.

20 6. A process for precooling and prepurifying a gaseous mixture, which comprises passing a gaseous mixture through a precooled regenerator chamber whilst passing a fraction of cold gas through a second chamber of a pair of alternating regenerator chambers surrounded by heat insulating material, and absorbing heat from the portions of said insulating material surrounding the chambers, from which cold losses occur in an amount sufficient to compensate for heat absorbed by said insulating material from external sources.

25 7. A process for precooling and prepurifying a gaseous mixture, which comprises passing a gaseous mixture through a precooled regenerator chamber whilst passing a fraction of cold gas through a second chamber of a pair of alternating regenerator chambers surrounded by heat insulating material, and passing through a restricted path in the portions of said heat insulating material surrounding the chambers from which cold losses occur, a fluid at a temperature sufficiently low to absorb heat passing through the insulating material from outside to the heat transfer chambers, whereby heat from external sources is compensated.

30 8. A process for precooling and prepurifying a gaseous mixture, which comprises passing a gaseous mixture through a precooled regenerator chamber whilst passing a fraction of cold gas through a second chamber of a pair of alternating regenerator chambers surrounded by heat insulating material, and passing back and forth through a restricted path in said heat insulating material surrounding the chambers from which cold losses occur, a fluid at a temperature sufficiently low to absorb heat passing through the insulating material from outside to the heat transfer chambers, whereby heat from external sources is compensated.

35 9. An improved heat transfer device for precooling and prepurifying a gaseous mixture which comprises a pair of alternating regenerators surrounded by heat insulating material, and a conduit passing back and forth in said heat insulating material forming a cold shield over said regenerator walls from which cold losses occur for conveying a heat absorbing fluid therethrough whereby heat from external sources passing through said heat insulating material can be absorbed.
